UNITED STATES PATENT OFFICE.

REGINALD R. HODGKINS, OF LOS ANGELES, CALIFORNIA.

DESIGN FOR A GOLF-CLUB HEAD.

Application filed March 18, 1926. Serial No. 16,978. Term of patent 3½ years.

To all whom it may concern:

Be it known that I, REGINALD R. HODGKINS, a citizen of the United States, residing at Los Angeles, in the county of Los Angeles and State of California, have invented a new, original, and ornamental Design for Golf-Club Head, of which the following is a specification, reference being had to the accompanying drawing, forming part thereof.

Fig. 1 is a front elevational view of a golf club head embodying my new design.

Fig. 2 is an end view of a golf club head embodying my new design.

I claim:

The ornamental design for a golf club head, as shown.

REGINALD R. HODGKINS.
